DRILLING MACHINE

George Heinish, Cuyahoga Falls, and Leo A. Krupp, Akron, Ohio, assignors to The Star Drilling Machine Company, Akron, Ohio, a corporation of Ohio

Application January 24, 1931. Serial No. 510,916

1 Claim. (Cl. 255—7)

This invention relates to well drilling rigs or machines of the usual mobile type in common use for drilling oil and gas wells or blasting holes, and the chief objects of the invention are to 5 avoid wear on the drill rope during the "spudding" operation; to distribute the drilling strain equally on both sides of the machine; to absorb the drilling shock of the drill rope during spudding; and to effect level or uniform winding of 10 the drill rope on the bull reel.

Of the accompanying drawings,

Figure 1 is a side elevation of a drilling machine embodying the invention in its preferred form, a part of the machine including the power plant being broken away;

Figure 2 is a sectional plan view on a larger scale on the line 2—2 of Figure 1;

Figure 3 is a plan view on a larger scale on the line 3—3 of Figure 1;

Figure 4 is a detail side elevation on a larger scale of an improved pitman constituting a part 20 of the machine; and

Figure 5 is a detail side elevation of a modified pitman structure.

Referring to the drawings, the machine is of 25 open frame construction comprising two longitudinal beams or girders 10, 10 connected at suitable intervals by cross-girders, such as that shown at 11, Figures 2 and 3. Suitable brackets

30 12, 12 are mounted on the under side of the girders 10 and carry the axles for the several sets of ground-wheels 13, 13 which carry the machine, the axles also serving to space and stiffen the machine frame.

35 Rising from each side girder 10 at the front end of the machine (the right end as viewed in the drawings) are respective uprights or standards 14, 14 which carry respective brackets 15, 15 at their upper ends, said brackets being connected by a bar or rod 16 which serves as a cross-brace for the uprights and also serves as a fulcrum shaft for a mast 17 which is supported thereupon by means of C-clamps 18, 18. The uprights 14 also are braced by respective props 40 19 secured to the girders 10 of the machine. The mast 17 comprises two lateral members 17^a, 17^a which are suitably cross-braced, and taper toward each other at their upper ends wherein a grooved sheave or pulley 20 is journaled. A 45 suitable pillow-block 21 is provided for the base of the mast when it is in upright position.

50 Rising from each side girder 10 adjacent the rear of the machine are respective uprights or standards 22, 22 which are braced by suitable props 23 from the machine frame and carry at

their upper ends a stationary bar or fulcrum shaft 24 which is secured to the uprights 22 by suitable clamps 25, 25. Pivotedly mounted upon the end portions of the shaft 24, outside the uprights 22, is a spudder 26 comprising longitudinal girders 26^a, 26^a and cross girders 26^b, 26^b. The free ends of the girders 26^a are positioned beside the uprights 14 and engage suitable wear-plates 27 thereupon, the arrangement assuring lateral stability of the spudder.

For oscillating the spudder 26 upon its pivot 24, a transverse bar or fixed shaft 28 is disposed transversely of the spudder and secured to the respective girders 26^a adjacent the free ends thereof, and pivotally connected to the end portions of 60 said bar 28 are respective pitmans 29, 29 which have their other ends connected to the crank pins of respective cranks 30, 30 mounted upon the opposite ends of a driven shaft 31 which is suitably journaled upon the girders 10 transversely of the machine. For driving the shaft 31, a pulley 32 is mounted thereon and connected by a transmission belt 33 with a pulley 34 journaled on a countershaft 35, said pulley 34 being 65 provided with one member 66 of a suitable clutch 70 subsequently to be described. The countershaft 35 is provided with a sprocket 36 which is connected by a sprocket chain 37 with a suitable power unit (not shown).

In order to absorb the drilling shock of the drill 75 rope and thus to avoid vibration and jolting of the machine, there is provided a yielding connection between the fixed shaft 28 and the respective pitmans 29, the construction of which is best shown in Figure 4. That end of each pitman 90 29 which engages the fixed shaft 28 is provided with a pair of parallel guide-rods 38, 38 which extend beyond the end of the pitman, a bearing block 39 for the shaft 28 being slidably mounted upon said rods 38, and a pillow-block 95 40 of yielding material, such as rubber, being positioned between the bearing block 39 and the end of the pitman. A yoke 41 connects the outer ends of the guide rods 38, and a compression spring 42 is mounted between said yoke and the 100 bearing block 39.

In the drilling operation known as spudding, the drilling tool 43 is suspended from one end of a drill rope 44, the latter passing over the pulley 20, under a grooved pulley 45 journaled on 105 the fixed shaft 28 of the spudder, over a grooved pulley 46 journaled upon the fixed shaft 24 constituting the fulcrum of the spudder, the remainder of the rope being wound upon a bull-reel 47 which winds up or pays out the rope as 110

desired. Oscillation of the spudder 26 effects reciprocating longitudinal movement of the drill-rope 44 between the pulley 45 and the tool 43 whereby the latter is alternately raised and lowered to effect penetration of the soil. A retaining plate 48 is adjustably mounted upon the forward cross-brace 26^b and has one edge positioned close to the perimeter of the pulley 45 to prevent the drill-rope 44 from jumping out of the groove in the pulley during the spudding operation.

As hereinbefore stated, the pulleys 45, 46 are journaled on the respective shafts 28 and 24, and they have axial movement on said shafts within the limits defined by respective pairs of stop collars 49, 49, 50, 50 on said shafts. As is shown in Figure 3, the collars are positioned at each side of the pulleys, and the collars 50 on the shaft 24 are positioned somewhat farther apart than are the collars 49. The arrangement permits the pulley 46 to move back and forth to feed the rope 44 evenly onto the bull-reel 47 without diverting the rope at such an angle as to cause it to climb out of the groove in either pulley 45 or 46.

The bull-reel 47 is mounted upon a shaft 49 that extends transversely of the machine and is suitably journaled on the girders 10 thereof. The end portions of the shaft extend beyond its journals, and at one end a sprocket 50 is mounted thereon and connected by a sprocket chain 51 with a sprocket 52 which is mounted upon a member 53 journaled on the countershaft 35, said member constituting one part of a clutch, the other member 54 of which is slidably keyed to said shaft. The clutch member 54 is provided with a shipper-lever 55 that is pivoted at one end on a support 56 that extends transversely of the frame girders 10, the other end of the shipper-lever being connected by a link 57 to a bell-crank 58 that is pivotally mounted at 59 and has an operating rod 60, Figure 2, that extends to the front of the machine. The arrangement provides means for driving the bull-reel to wind the drill-rope 44 thereon.

The drill-rope is let off from the bull-reel while the driving clutch is disengaged, the weight of the tool 43 and drill-rope being sufficient to rotate the reel and its shaft. For controlling the speed of the let-off, the opposite end of the shaft 49 is provided with a brake drum 61 that is engaged by a brake band 62, one end of the latter being fixedly mounted and its other end connected to a bell crank 63 that is pivotally mounted at 64, Figure 1, and provided with an operating rod 65 that extends to the front of the machine.

The clutch member 66 of the pulley 34 is adapted to be engaged with the other member 67 of the clutch, said member 67 being slidably keyed upon the countershaft 35 and operated by a shipper lever 68 that is pivoted at one of its ends on the support 56 and has its other end connected by a link 69 to a bell crank 70 that is pivotally mounted at 59. An operating lever 71 is connected to the bell crank and extends therefrom to the front of the machine.

In general, the drilling machine is operated in the usual manner, the countershaft 35 being constantly driven, and the pitmans 29 alternately raising and lowering the spudder 26 to reciprocate the drilling tool 43 in the drill hole. The feature of the double pitman drive distributes the drilling strain equally on both sides of the machine frame, and the yielding connections between the pitmans and the spudder act as shock absorbers to absorb the drilling shock of the drill-rope. The absorbing of this shock in the pitmans instead of in rigidly mounted drill-rope pulleys, as has been the custom heretofore, obviates such relative movement of the pulleys and drill-rope as would wear the latter and shorten its useful life. The mounting of the pulleys 45, 46 by which each of them is permitted limited axial movement assures uniform spooling of the drill-rope on the bull-reel and lessens the chances of the drill-rope coming out of the groove in either pulley.

In Figure 5, there is shown a modified form of pitman consisting of a split bearing block 75 adapted to engage the crank pin of a crank 29, a pair of elongate parallel rods 76, 76 secured at one of their adjacent ends to the bearing block 75 and having their other ends connected by a yoke 77. At an intermediate position on the rods 76 is secured a plate or support 78 which supports a cushion or block 40^a of resilient rubber, and resting against the upper face of the cushion 40^a is a bearing block 39^a adapted to receive the fixed shaft 28 of the spudder. A compression spring 42^a is mounted between the upper face of the bearing 39^a and the lower face of the yoke 77 for urging the bearing block 39^a yielding toward the cushion 40^a.

Other modifications are possible within the scope of the appended claims which are not limited wholly to the specific construction shown and described.

What is claimed is:

A drilling machine including a mast, a pivotally mounted spudder beam, a bull reel, and a drill rope on said reel, said mast having a sheave 120 thereon above the spudder beam, said spudder beam having longitudinally spaced sheaves thereon, one adjacent the reel and the other adjacent the mast, and said drill rope extending from the bull reel about the first-named sheave to the second-named sheave and then over the sheave on the mast and having a drilling tool on the free end thereof, the sheaves on the spudder beam being mounted thereon for substantial transverse axial movement, the sheave adjacent the reel being 125 movable to a greater extent than the sheave adjacent the mast to follow the side play of the drill rope to maintain the drill rope stretches between the reel and the first-named sheave, between the sheaves on the spudder beam and between the spudder beam and the mast in substantial alignment in a vertical plane at all times as the drill rope is wound or unwound from the reel.

GEORGE HEINISH.
LEO A. KRUPP.
